UNITED STATES PATENT OFFICE.

ANDREW RASMUSSEN, SR., AND ANDREW RASMUSSEN, JR., OF RIDGWAY, COLORADO.

INTERNAL-COMBUSTION MULTIPLE-CYLINDER ENGINE.

1,220,455.

Specification of Letters Patent. Patented Mar. 27, 1917.

Application filed April 14, 1916. Serial No. 91,086.

To all whom it may concern:

Be it known that we, ANDREW RASMUSSEN, Sr., and ANDREW RASMUSSEN, Jr., citizens of the United States, residing at Ridgway, in the county of Ouray, State of Colorado, have invented a new and useful Internal-Combustion Multiple-Cylinder Engine; and we do hereby declare the following to be a full, clear, and exact description of the invention, such as will enable others skilled in the art to which it appertains to make and use the same.

This invention relates to an improved internal combustion multiple cylinder engine including a single driving crank shaft, to which the pistons of the cylinder are connected, to insure uniform speed of the shaft.

One of the objects of the invention is to provide an engine of this kind, which is simple, efficient and practical in construction.

Another object of the invention is to provide an engine, which is designed economically with respect to construction, compactness, and material.

Another object of the invention is the provision of a multiple of cylinders on a single crank shaft.

A further object of the invention is to provide an engine of this kind having a rotary slide valve, for coöoperating with all ports for intaking live charges and exhausting utilized gases.

Another object of the invention is to provide means for timing the firing of the multiple of cylinders automatically and correspondingly with the speed of the engine. In other words, should the engine be running at a low rate of speed, the charges will be correspondingly fired, and when the engine speed increases, the charges are fired more rapidly.

Another object of the invention is the provision of means which are operated by centrifugal force for controlling the firings of the charges correspondingly to the speed of the engine.

Another object of the invention is to provide an engine so constructed as to facilitate overhauling or repairing.

Another object of the invention is to provide an improved engine, to which all required devices and appliances, such as roller bearings, carburetor, magneto, spark plugs, etc., of conventional construction, may be

applied, without redesigning, or altering the design of the engine.

In practical fields the details of construction may necessitate alterations, falling within the scope of what is claimed.

The invention comprises further features and combination of parts, as hereinafter set forth, shown in the drawings and claimed.

In the drawings:

Figure 1 is a view in elevation of the improved engine constructed in accordance with the invention, showing the spark plug actuating devices, and the rotary slide valve member.

Fig. 2 is a view in elevation of the engine, illustrating the face thereof opposite to that shown in Fig. 1, and illustrating the intake and exhaust manifold pipes.

Fig. 3 is a sectional view of the engine, showing the revoluble slide valve member, and the multiple of cylinders, and illustrating the intake and exhaust ports, and the relative positions of the pistons.

Fig. 4 is a sectional view on line 4—4 of Fig. 3.

Fig. 5 is a sectional view on line 5—5 of Fig. 3, showing how the utilized gases are exhausted from one of the cylinders.

Fig. 6 is a sectional view on line 6—6 of Fig. 3 showing the intake of a charge in one of the cylinders.

Fig. 7 is a sectional view on line 7—7 of Fig. 3, showing how the revoluble slide valve member or ring covers the intake and exhaust ports, during the stage of compression of a charge in one of the cylinders.

Fig. 8 is an enlarged detail perspective view of the sparking mechanism carried by the revoluble slide valve.

Referring more especially to the drawings, 1 designates the engine casing, which is circular as shown, and is provided with an innermost annular wall 2, which connects integrally with the opposite correspondingly constructed circular or disk walls 3 and 4, 100 the greater central portions of which are cut away to form openings 5, which are covered by the plates 6 bolted by means of the bolts 7 to the walls 3 and 4. The annular wall 2 provides a crank chamber 8. The 105 walls 3 and 4 are cut away to provide the openings 5, so that by removing the plates 6 access may be had to the interior of the crank chamber. The plates 6 are provided with suitable bearings 9, in which the crank 110

shaft 10 having the crank 11 is journaled. Extending about the crank pin 12 of the crank is a U-shaped strap 13, the ends 14 of which are bolted to opposite sides of the pitman 15 by means of the bolts 16, thereby connecting the pitman to the crank pin, there being a filler block 17 between the crank pin and the end of the pitman which is connected to said straps. Also loosely mounted upon the crank pin is a pair of circular plates or disks 18, between which the strap 13 is arranged. As shown clearly in Fig. 3 there is a multiplicity of cylinder engines, and for the sake of clearness, and enabling them to be distinguished one from the other, they are designated respectively *a*, *b*, *c*, *d* and *e*, and mounted in these cylinders are the pistons *a'*, *b'*, *c'*, *d'* and *e'*. The piston *a'* is connected to the pitman 15 by the pin 19, and connected respectively to the other pistons by the pins 20 are the pitmen 21, 22, 23 and 24, which are in turn pivotally connected to the disks or circular plates 18 by means of the pins 25. The cylinders *a* to *e* inclusive have their heads 26 provided with threaded openings 27, into which the extensions 28 of the annular wall 29 of the casing 1 are threaded. These extensions 28 extend radially and have ports or openings 30, 31, 32, 33 and 34. The cylinders *a* to *e* inclusive near their other ends are provided with annular flanges 35, which are threaded into the openings 36 of the annular wall 2 of the casing 1, by which construction and the threaded connections at 27 the cylinders *a* to *e* inclusive are held firmly in position. As shown in Fig. 4 the wall 29 of the casing 1 is inclined or conical, and said casing 1 is provided with an annular flange 38, the portion 39 of which overhangs and is spaced apart from the conical wall 29, thereby providing a wedge-shaped channel 40, in which the annular valve ring 41 revolvably slides or rotates. A plurality of plates 42 are secured by screws 43 to the overhanging portion 39 of the flange 38, and are designed to overlie the annular valve ring 41, thereby retaining the ring in said channel 40. The annular valve ring 41 has a plurality of spark plugs 44, 45 and 46 threaded through its wall, and where the sparking terminals 47 of said plugs protrude on the inner part of the annular valve ring sparking chambers 48 are formed, which, as the valve ring slidably rotates in the channel, register with the ports or openings 30 at the time of firing in the respective cylinders. Adjacent the wall 3 of the casing the polygonal shaped intake manifold and annular or circular exhaust manifold pipes 51 and 52 are arranged, which pipes are provided with lateral extensions 53 and 54, which are tubular and are threaded into the ports 55 and 56; 57 and 58; 59 and 60; 61 and 62; and 63 and 64. The intake and exhaust manifold pipes 51 and

52 have connected thereto the main intake and exhaust manifold pipes 65 and 66, as shown clearly in Fig. 2. The valve ring 41 is provided with intake ports 67, 68 and 69, and exhaust ports 70, 71, and 72, which are 76 designed to register respectively with and between the ports 30 to 34 and the ports 56 to 64 inclusive, when intaking charges, and when exhausting utilized gases into and from the different cylinders alternately with 75 each other. The valve ring 41 is provided with a flange 74, partly overhanging the wall 4 of the casing 1, and this flange 74 is provided with a series of gear teeth 75. Carried on a stub pin 76 projecting from the wall 4 rotatably is a gear 77, which meshes with the teeth 75 of the valve ring. Rotatably mounted upon a stub pin 78 which projects from the annular or circular plate 6 is a gear 79, which meshes with the gear 77. 80 Keyed to the crank shaft 10 as shown at 80 is a gear 81, which in turn meshes with the gear 79. It is to be seen that by this chain of gears motion is transmitted from the crank shaft 10 to the valve ring 41, so that 85 its various ports will register with and between the ports 30 to 34 inclusive, and the ports 55 to 64 inclusive. The valve ring 41 adjacent the spark plugs has pivoted thereon by means of the screws 83 angular 90 weighted members 84. Each member 84 is provided with two arms 85 and 86. The arm 85 is substantially V-shaped, but may be any other suitable shape, and is provided with a binding screw or post 87 and a 95 contacting terminal 88, there being a wire or lead 89 extending from the binding post 87 to the spark plug. The arm 86 has a weight 90, and secured to the valve ring by means of suitable screws 91 is a plate 92, the end 10 93 of which acts as an abutment for the arm 85 of the angular member 84. A leaf spring 94 is secured by screws 95 to the other end of the bar 92, and has its free end bearing against the arm 86, thereby holding the arm 11 85 toward and against the end 93 of the bar 92. Carried by the wall 4 is a plurality of lugs 97, and secured to each of the lugs are the yieldable blades 98 and 99 having contacting terminals 100 and 101. Where each 1 of the blades 98 is secured to its lug 97 a binding post 102 is provided, and connecting the binding posts 102 are the wires or leads 103, 104, 105 and 106, and the leads or wires 107 and 108 from the lowermost binding post 102 in Fig. 1 are designed to connect to some suitable source of current supply. It is to be noted that as the valve ring 1 revolvably slides in its channel 40, the contacting terminals 88 sweep against the yieldable blades 99, thereby causing the contacting terminals 100 and 101 to contact, thereby closing the circuit and causing the spark plug to fire the charge. It is to be observed that when the engine is running at a low 1

rate of speed the sparking of the spark plugs is retarded, owing to the arms 85 being in contact with the end 93 of the bar 92. However, just so soon as the speed of the engine increases, the weighted arms 86 of the angular members 84 swing outwardly owing to the centrifugal force, against the action of the spring blades 94, thereby advancing the spark of the spark plug. A water space 115 is formed between the walls 2 and 29 of the casing, and into which space water is conveyed from any suitable source through the pipe 116, for cooling the cylinders, and which water is carried off through the pipe 117.

Operation.

The operation will be understood by first assuming, that the piston a' of the cylinder a is in firing position, the piston b' being substantially midway the intake stroke, the piston c' about to complete its firing stroke, the piston d' about having begun its compression stroke, while the piston e' is substantially midway its exhaust stroke. With respect to these relative positions of the multiple of pistons, the various intake and exhaust ports 67, 68, and 69; and 70, 71, and 72, are positioned relative to the ports 30, 31, 32, 33, and 34; and 55, 56; 57, 58; 59, 60; 61, 62; and 63, and 64, whereby the above firing, intake, and about the complete firing, compression, and exhaust strokes may take place. While the piston a' is moving to complete its firing stroke as a result of the spark plug 44 having fired its charge, the valve ring will move in the direction of the arrow g , so that the exhaust port 70 will assume a position two-thirds of the space between the ports 30 and 31, and the port 67 out of registration with the ports 31 and 57 to a position one-third of the space between ports 30 and 31. This movement of the valve ring brings the exhaust port 71 in registration with the ports 32 and 60 for exhausting the gases from the cylinder c , the spark plug 46 in position to fire a charge in cylinder d , and the intake port 69 in registration with the ports 34 and 63, whereby an intake of a charge may take place in cylinder e . Again referring to cylinder a it is to be seen that when the piston a' is substantially midway its exhaust stroke (for instance, as represented by the piston e'), the valve ring has moved, so that the port 70 will complete the space between ports 30 and 31, bringing the port 70 in registration with the ports 30 and 56, whereby the piston a' may exhaust the utilized gases from the cylinder a . Therefore when the piston a' completes its exhaust stroke, the piston b' has completed its compression stroke (the spark plug 45 having reached the port 31 by this time, the compressed charge in cylinder b is fired), and in this case the intake 68 is in registration with the

ports 32 and 59, the piston c' about starting its intake stroke, the piston d' starting its exhaust stroke, while the piston e' is starting its compression stroke. Owing to the provision of the three intake ports and the three exhaust ports and the arrangement and the ratio of the gears 75, 77, 79 and 81, (the ratio of which gears in practice is to be six to one) the cylinders a , b , c , d and e will function alternately in the direction of rotation of the valve and crank shaft, in view of which the table below may be followed.

Cylinders.	Strokes.	Strokes.	Strokes.	Strokes.	80
a	Firing	Exhaust	Intake	Compression.	
b	Intake	Compression	Firing	Exhaust.	
c	Firing	Exhaust	Intake	Compression.	85
d	Compression	Firing	Exhaust	Intake.	
e	Exhaust	Intake	Compression	Firing.	90

The invention having been set forth, what is claimed as new and useful is:

1. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel, a valve ring slidable revolvably in the channel, said cylinders having ports of communication with the channel, the outer wall of the channel having an intake and an exhaust port for each cylinder, said valve ring having a plurality of intake and exhaust ports for registering with the ports of the cylinders and the intake and exhaust ports of the outer wall of the channel, for intaking and exhausting charges.

2. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel, a valve ring slidable revolvably in the channel, said cylinders having ports of communication with the channel, the outer wall of the channel having an intake and an exhaust port for each cylinder, said valve ring having a plurality of intake and exhaust ports for registering with the ports of the cylinders and the intake and exhaust ports of the outer wall of the channel, for intaking and exhausting charges, spark plugs carried by the valve ring, said casing having a plurality of electrical contacting terminals, and means carried by the ring and electrically connected to the spark

4
plug and coöperating with the terminals of the casing for alternately operating the spark plugs.

3. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel, a valve ring slidable revolvably in the channel, said cylinders having ports of communication with the channel, the outer wall of the channel having an intake and an exhaust port for each cylinder, said valve ring having a plurality of intake and exhaust ports for registering with the ports of the cylinders and the intake and exhaust ports of the outer wall of the channel, for intaking and exhausting charges, and means of connection between the valve ring and the crank shaft for imparting motion to the valve ring.

4. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel wedge-shaped in cross section, a valve ring wedge-shaped in cross section slidable revolvably in the channel, said cylinders having ports of communication with the channel, the outer wall of the channel having intake and exhaust ports for each cylinder, said valve ring having a plurality of intake and exhaust ports for registering with the ports of the cylinders and the intake and exhaust ports of the outer wall of the channel for intaking and exhausting charges, and spark plugs carried by the slidale valve ring.

5. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel wedge-shaped in cross

section, a valve ring wedge-shaped in cross section slidable revolvably in the channel, said cylinders having ports of communication with the channel, the outer wall of the channel having intake and exhaust ports for each cylinder, said valve ring having a plurality of intake and exhaust ports for registering with the ports of the cylinders and the intake and exhaust ports of the outer wall of the channel for intaking and exhausting charges, said valve ring having an overhanging flange provided with gear teeth, a train of gears carried by the casing coöperating with the gear teeth of the valve ring and having a gear connection with the crank shaft for imparting motion to the valve ring.

6. In a multiple cylinder internal combustion engine, a casing, a multiple of radially disposed cylinders, a crank shaft mounted in bearings of the casing, pistons operable in the cylinders and being connected respectively to the crank shaft, said casing having an outer wall provided with an annular channel, a valve ring slidable revolvably in the channel, said cylinders having ports of communication with the channel, the outer wall of the channel having an intake and an exhaust port for each cylinder, said valve ring having a plurality of intake and exhaust ports for registering with the ports of the cylinders and the intake and exhaust ports of the outer wall of the channel, for intaking and exhausting charges, spark plugs carried by the valve ring, said casing having a plurality of electrical contacting terminals, and means carried by the ring and electrically connected to the spark plug and coöperating with the terminals of the casing for alternately operating the spark plugs, and means for advancing and retarding the spark.

In testimony whereof we have signed our names to this specification in the presence of two subscribing witnesses.
